US00D379310S

United States Patent [19]

Balz

[11] Patent Number: Des. 379,310

[45] Date of Patent: **May 20, 1997

[54] LIQUID CHEMICAL CONCENTRATE BOTTLE

[75] Inventor: Eric R. Balz, Eagan, Minn.

[73] Assignee: Ecolab Inc., St. Paul, Minn.

[**] Term: 14 Years

[21] Appl. No.: 36,912

[22] Filed: Mar. 30, 1995

[51] LOC (6) Cl. 09-01

[52] U.S. Cl. D9/537; D9/523; D9/556

[58] Field of Search D9/300, 523, 526, D9/537, 540, 556, 557, 520; D23/225; 215/382, 383, 384; 222/383.1

[57] CLAIM

The ornamental design for a liquid chemical concentrate bottle, as shown and described.

DESCRIPTION

FIG. 1 is a perspective view showing a preferred embodiment of my new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top view thereof;

FIG. 7 is a bottom view thereof;

FIG. 8 is a top plan view of a second embodiment of the liquid chemical concentrate bottle; and,

FIG. 9 is a right side elevational view of the second embodiment.

The second embodiment of the bottle is the same as the first embodiment except for the placement of the arcuate recess on the shoulder of the liquid chemical concentrate bottle.
